Primary Examiner—Stacia Cadmus*(74) Attorney, Agent, or Firm*—Leon E. Redman; Lloyd D. Doigian(57) **CLAIM**

The ornamental design for a hitch mountable cargo carrier, as shown and described.

DESCRIPTION

FIG. 1 is a perspective view of the hitch mountable cargo carrier showing our new design;

FIG. 2 is a top plan view thereof;

FIG. 3 is a rear elevational view thereof;

FIG. 4 is a bottom plan view thereof;

FIG. 5 is a left side elevational view thereof, the right side being a mirror image of the left shown; and,

FIG. 6 is a front elevational view thereof.
